BOMB

Don B. McCloud, Carbondale, Ill., George A. Lewis, New Dorp, N. Y., and Christian G. Storm, Arlington, Va., assignors to the Government of the United States of America, as represented by the Secretary of War

Application May 9, 1939, Serial No. 272,568

2 Claims. (Cl. 102—2)

This invention relates to a bomb and more particularly to a bomb of the type adapted to be charged with a liquid oxygen explosive. The disclosure hereinafter made relates to a demolition or fragmentation bomb so constructed as to be conveniently attached to and launched from aircraft, but it is not to be construed as limited to an aerial drop bomb, as the features of the invention are generally applicable in any type bomb employing a liquid oxygen explosive agent.

Liquid oxygen in combination with a combustible absorbent agent has long been recognized as an efficient high explosive in the mining and similar industries and its use has been proposed for military purposes heretofore.

There are, however, several obstacles in the convenient and safe use of liquid oxygen explosive and these are coupled with the inherent characteristic of liquid oxygen, namely; to rapidly evaporate when subjected to a temperature above its boiling point of —182 degrees centigrade and its tendency or ability of being easily detonated when incorporated with a combustible ingredient and brought into contact with a ferrous metal container. These obstacles present a serious problem in connection with the employment of liquid oxygen explosive as the explosive charge in a demolition bomb as they place limitations upon the use of the explosive, that is, limitations upon the time within which the bomb must be used after being charged with the liquid oxygen explosive and manner in handling, which are in direct conflict with military requirements, and it is, therefore, an object of this invention to provide a bomb so constructed as to in a large measure overcome these obstacles.

It is a further object of this invention to prolong the efficient life of a liquid oxygen explosive charge in a demolition bomb by reducing evaporation of the liquid oxygen to a minimum through the use of an effective heat insulant so arranged as to substantially completely enclose the explosive charge.

It is another object of the invention to so arrange the steel or other ferrous alloy bomb body so that the explosive charge will be secured in spaced relation from the bomb body by the insulating medium to reduce thermal short circuits to a minimum.

It is a still further object of the invention to provide a bomb structure adapted to be charged with liquid oxygen explosive and so constructed that the bomb may be wholly assembled including all elements of the explosive mixture, except the liquid oxygen, and so arranged that the bomb

may be conveniently and safely armed by addition of the liquid oxygen at a charging station located at any desirable place.

It is still another object of the invention to provide a bomb structure adapted to be charged with liquid oxygen explosive that lends itself to ready production through the utilization of commercially available prepared cartridges such as shown in U. S. Patent Nos. 1,863,921—2,074,553 and Re. 19,410 and at present employed in a blasting explosive identified as "Airmite."

The specific nature of the invention as well as other objects and advantages thereof will clearly appear from a description of a preferred embodiment as shown in the accompanying drawing in which:

Fig. 1 is a longitudinal sectional view of a bomb embodying the invention;

Fig. 2 is a cross-section taken on the line 2—2 of Fig. 1;

Fig. 3 is a longitudinal sectional view of a bomb embodying a modification of the invention, and

Fig. 4 is a fragmentary view partially in section showing a modified form of vent for the liquid oxygen explosive container.

Referring now to the drawing by numerals of reference and wherein the same numeral refers to the same element throughout the views, there is shown in the form of the invention of Figs. 1 and 2 a bomb of the aerial drop type having an outer conventional casing 10 made of steel or other suitable ferrous alloy and comprising the generally cylindrical casing body 11 and nose 12 secured thereto in any suitable manner, such as by welding.

The casing 10 may be made of such size and thickness or weight as the service of a particular bomb requires and is provided within its nose 12 with an inwardly extending axially arranged tubular protuberance 13 flanged at its terminal 14 for a purpose to be hereinafter more particularly set forth.

The nose 12 is packed with a material 15 of low thermal conductivity, such as mineral wool, which is retained therein by means of an annular or suitable segmental spacer 16 also of low thermal conductivity in cooperation with the liquid oxygen explosive container 21 hereinafter described. Superimposed upon the spacer 16 is a prefabricated and preferably light weight sheet 17 of low thermal conducting substance of suitable thickness and mechanical strength. This material may be obtained commercially in sheets and cut to desired size. Insulation of the type made from the hulls of certain tropical nuts and

known commercially as "Dry Zero" has been found to be very efficient. To facilitate assembly of the annular sheet of insulation 17 within the bomb casing body 11 of the bomb and to provide proper support for the liquid oxygen container 21 along its length the sheet 17 may be divided into a plurality of superimposed decks as indicated at 18 separated by interposed spacers 19 of the same general type as spacer 16. To further expedite support of the liquid oxygen explosive container 21 a spacer 20 may be superimposed upon the deck 18 in proximity of the end of the bomb casing remote from the nose 12.

A liquid oxygen explosive container 21 of non-ferrous substance, such as copper and preferably having a body portion 22 of cylindrical shape joined to an outwardly dished bottom portion 23 provided with an inwardly directed central gibbosity 24 of general truncated conical form is employed to confine the explosive mixture within the bomb casing and is of such diameter as to snugly fit within the cylindrical bore formed by the insulation sheet 17 in supportingly or embracingly engaged relation by the spacers 16, 19, 20 and of such length as to be axially supported at one end by tubular protuberance 13, through interengagement of the flange 14 and truncation of gibbosity 24, and extend a slight distance beyond spacer 20 at its opposite end. If desired the bottom 23 of container 21 may be made flat, but we prefer to employ a dished bottom of the type above described and shown in Fig. 1 as by such expedient we are enabled to materially increase the capacity of the container 21, especially in large size bombs, without reducing the depth of the thermal insulation surrounding the container or creating any thermal short circuits. The container 21 is provided with a flanged or other suitable closure 25 of non-ferrous substance apertured centrally at 26 and adjacent its periphery at 27 to provide for the outward extension of a perforated filling tube or pipe 28 and vent tube or pipe 29, respectively. For convenience in assembling the filling and vent tubes may be secured to the closure 25 in any appropriate manner.

The bomb casing 10 is closed by a closure 30 adapted to be secured to the bomb casing in any desired manner, as by welding, and is apertured to form passages in alignment with the apertures 26 and 27 for the outward protrusion of the filling and vent tubes, respectively. The closure 30 has secured thereto a conventional stabilizing fin assembly 31 with provision made for the protrusion of the filling tube 28 therethrough to a point adjacent its trailing terminal for facility in filling the container 21.

Container 21 is charged with absorbent carbonaceous material packed in cartridges after the manner generally disclosed in U. S. Patent Re. 19,410 above referred to. To facilitate insertion of the cartridges within container 21 about filling tube 28 the cartridges are formed in arcuate sections as indicated at 32 in Fig. 2 and to increase the efficiency of the explosive mixture as well as expedite assembling, the cartridges 32 are disposed in a plurality of decks 33 and in slightly spaced relation both between decks and the individual cartridges comprising decks. This expedient reduces the time of subsequently saturating the carbonaceous absorbent material in the cartridges as a greater area of the cartridges is presented to unobstructed penetration by the liquid oxygen when added. The cartridges of the lowermost deck 33 are supported at their outer

edges on the inwardly directed peripheral portion of the bottom 23 and at their inner edges on the truncation of gibbosity 24 so as not to obstruct the reservoir 34 formed in the bottom 23 and the whole cartridge assembly is retained in position by the spacers 35 interposed between the closure 25 and adjacent end of the cartridge deck 33.

Bulk material 36 of low thermal conductivity, which may be the same as material 15, is packed between spacer 20, closure 25 and closure 30 to substantially complete thermal isolation of the container 21 with respect to the bomb casing 10 and closure 30.

Although we are aware that impact may be relied upon to detonate some liquid oxygen explosive mixtures we prefer to employ a fuse generally indicated at 37, located in the nose 12 of the bomb casing and provided with a detonating train of conventional construction leading through the tubular protrusion 13 to the explosive mixture in container 21 as indicated diagrammatically at 38. The fuse 37 may be of the impact or delay type or a combination of the two of any conventional construction.

In assembling the bomb structure of our invention we first extend the filling pipe 28 into the container 21 axially thereof and in engagement with the bottom 23. The first deck of cartridges 33 are then arranged around the filling pipe and succeeding decks similarly arranged until the container is filled. The height of the cartridge assembly with respect to the container 21 is so chosen that a vent space 39 will be provided between the cover 25 and top deck of cartridges within which evaporated oxygen may accumulate. The spacers 35 are then inserted and the cover 25 positioned on container 21 with the filling tube 28 protruding through aperture 26 and secured to the container by any appropriate means such as soldering. The vent 29 is next secured to cover 25 in such manner as to establish communication between atmosphere and the vent space 39 through aperture 27 and the gaps between spacers 35 and is soldered or otherwise suitably secured to the cover 25 in this position. The filling tube 28 is then raised to its operative position and secured to cover 25 to complete assembly of this unit of the bomb.

The bomb casing 10 is now placed in a vertical position and the nose 12 packed with material 15 to an appropriate depth. The first spacer 16 is next inserted in the bomb casing after which the container 21 charged with its carbonaceous cartridges and provided with the spacers 35, closure 25, filling tubes 25 or 41 and vent tubes 29 or 43 is lowered into the casing to be embraced by the spacer 16 and supportingly engaged on member 13-14. Thereafter, in order, the decks of insulant 18 and spacers 19 are positioned within the space between the bomb body and container 21 until this space is filled and then spacer 20 is superimposed upon the top deck 18 of insulant. Insulating material 38 is now packed above the spacer 20 and top of container 21 to the level of the top of the bomb body and cover 30 with its fin assembly if it is to be so provided is placed in position and secured to the bomb body. If desired the filling tube 28 and vent pipe 29 may be secured to the cover 30 as by brazing or other suitable means. The bomb is now ready to be armed with the fuse and saturated with liquid oxygen and may be safely stored in this state of assembly until required for use at which time it may be armed and saturated.

When the bomb is saturated such operation should be performed in the vertical position of the bomb by introducing the liquid oxygen through the filling tube 28. Upon initial introduction of the liquid oxygen there is considerable evaporation due to the absorption of heat from the container 21 and the filling must be slowly accomplished, however, as the temperature gradient between the liquid oxygen and container 21 decreases the rate of filling may be increased. The liquid oxygen goes through the perforations in the tube 28 and is absorbed by the cartridges with surplus liquid collecting in the reservoir in the nose of the container 21 and between the cartridges to prolong the effective life of the bomb by replacing the liquid evaporated. After the container 21 is completely filled a cap 40 is secured on the end of the filling pipe and evaporated oxygen will collect in the vent space 39 and discharge to atmosphere through vent tube 29 to eliminate building up a pressure in the bomb. The vent tube may be curved as shown in Fig. 1 so that liquid cannot escape in the horizontal position of the bomb. If desired or necessary the bomb may be filled with liquid oxygen in the horizontal position by connecting an elbow on the filling pipe 28.

The life of a bomb built in accordance with the disclosure is very materially increased and if not used before the expiration of its efficient life may be revived by the introduction of additional liquid oxygen to replace that lost through evaporation.

In the modification of the invention shown in Fig. 3 elements corresponding to similar elements of the invention as shown in Fig. 1 have been identified by like numerals. The bomb of this form of the invention is intended to be of much smaller capacity and therefore the container 21' is provided with a flat bottom 23' in as much as the additional capacity obtained by the dished bottom is not sufficient to justify its use. Also we have consolidated the filling tube and vent tube into a unitary structure as indicated at 41. The tube 41 is constructed of such diameter that the container 21' may be filled therethrough while at the same time providing for the escape of evaporated oxygen. The filling tube closure 42 is pierced by the vent tube 43 which leads from the vent space 39.

The cartridges are in this case circular in section and packed in general accordance with the U. S. reissue patent above referred to. The container 21', depending upon its length may be charged with one or more cartridges, but in this regard we have discovered that it is difficult to pack the cartridges with "Airmite" lampblack and obtain uniformity of packing in lengths greatly in excess of 24 inches.

In those cases where a vent tube of the type

heretofore described and shown in Figs. 1 and 3 at 29 has an undesired siphoning effect on the oxygen in the vent space 39 it is proposed to use the modified form of vent shown in Fig. 4. In this form of the invention the vent 29' is formed to extend without the area of reduced pressure that exists at the trailing end of the bomb in flight and is provided with a funnel shaped mouth 29'' facing in the direction of flight. By 10 this means the siphoning effect on the oxygen accumulated in the vent space 39 by reason of having the mouth of the vent tube terminate in the area of reduced pressure at the trailing end of the bomb in flight is not only eliminated but 15 actually effects building a pressure up in the vent space 39 in excess of atmospheric pressure with consequent reduction in the vaporization rate of the liquid oxygen due to its corresponding change in boiling temperature. If the bomb is of such 20 capacity as to require a vent 29' and funnel 29'' of a size that disturbs the balance of the bomb in flight then a plurality of vents and funnels may be employed and symmetrically located so as to avoid disturbance of the balance of the bomb in flight.

Having now described what we at present regard as a preferred embodiment of our invention, what we claim as new and desire to secure by Letters Patent is:

1. In a liquid oxygen explosive bomb comprising in combination, an outer casing, an inner liquid gaseous explosive container disposed within the outer casing in spaced relation therefrom, filling means providing communication between the interior of the container and atmosphere and vent means communicating with the rear end portion of the container and atmosphere extending laterally without the space occupied by the outer casing and formed to present its exit 35 communicating with atmosphere facing in the direction of the normal forward end portion of the bomb.

2. In a liquid oxygen explosive bomb in combination, an elongated outer casing, an elongated container having imperforate side walls disposed in the casing with its side walls in spaced relation therefrom, a filling tube communicating with atmosphere extending interiorly a substantial length of the container axially thereof and being 40 perforated within said container, a closure for said filling tube, and vent means forming a vent passage leading from the interior of the container to atmosphere, and a fin assembly on the trailing end of said bomb, said filling tube extending axially through said fin assembly and being supported thereby.
